UNITED STATES PATENT OFFICE.

ONESIME H. LE COMPTÉ AND FRANK H. LE COMPTÉ, OF OKLAHOMA, OKLAHOMA,
ASSIGNORS, BY DIRECT AND MESNE ASSIGNMENTS, TO THE LE COMPTÉ STAND-
ARD AUTOMATIC DRAWBAR AND CONNECTOR COMPANY, OF DENVER, COLO-
RADO.

CAR COUPLING.

Application filed February 27, 1920. Serial No. 361,891.

To all whom it may concern:

Be it known that ONESIME H. LE COMPTÉ and FRANK H. LE COMPTÉ, citizens of the United States, residing in the city of Oklahoma, in the county of Oklahoma and State of Oklahoma, have invented new and useful Improvements in Car Couplings, of which the following is a specification, reference being had to the accompanying drawings.

10 Our invention relates to improvements in automatic car couplers.

Our primary object is to provide means of simple and inexpensive construction which will operate, with certainty under all ordinary conditions, to automatically couple cars.

A further object is to construct a coupler in a manner facilitating assemblage, having special regard for reducing the repair or up-
20 keep expenses.

A still further object is to provide a simple connection between the draw bar and coupling head arranged to permit relative vertical and rotative movement between the draw bar and coupling head.

A still further object is to provide means additional to the usual pivot pin for assisting the pivot pin in transmitting the draw bar pull to the coupling head.

30 With the foregoing objects in view, the invention consists in the novel construction, arrangement and combination of parts as hereinafter fully, clearly and concisely set forth, definitely pointed out in our claims and illustrated by the accompanying drawings, in which;

Figure 1 is a plan view of a pair of couplings, in coupled position, constructed in accordance with the invention.

40 Figure 2 is an elevation of the couplings, as shown in Figure 1.

Figure 3 is a longitudinal, vertical sectional elevation taken on the line 3—3 of Figure 1 the coupling pins being shown in
45 elevation.

Figure 4 is a sectional plan view taken on the line 4—4 of Figure 2.

Figure 5 is a transverse sectional view taken on the line 5—5 of Figure 1 looking
50 in the direction of the arrow.

Figure 6 shows a plan and an elevation view of the key plate hereinafter described.

Referring, by numerals, to the drawings. A and B designate the heads of the coupling, which are identical structures and which are 55 preferably of cast construction and whose design permits both to be formed in the same mold with a resultant economy in construction to which is added the feature that any coupler of this type may be employed 60 at either end of any car.

Inasmuch as the two heads are identical we will describe in detail the one head only, as follows:

Projecting forwardly from the front of 65 the head is a fixed jaw 1, occupying a position wholly to one side of the longitudinal median line, and which has formed on its inner face a vertical recess 2. On its outer, lateral face the jaw 1 is provided with a 70 longitudinal tapering rib 4. The jaw 1 with its recess 2 and rib 4 is preferably formed as an integral part of the head and said head except for the base of the said jaw is formed as a hollow shell, comprising a top wall 5, a 75 bottom wall 6 and side walls 7 and 8.

The opening 9, formed by the space between the base of the jaws 1 and the walls 5, 6 and 8, is of substantially the same area and contour as the jaw 1 and is arranged to 80 receive the jaw of a companion coupling, and, the wall 8 is provided with a way 10, of longitudinally tapering formation for the reception of the rib 4 of the companion coupling, and by this expedient the two heads 85 are brought to the same plane when brought together.

Projecting laterally from the base of the jaw toward the wall 8 is a stud 11 whose forward upper and lower corners are chamfered 90 and formed in the inside face of the jaw is a longitudinal channel 12 for the accommodation of the stud of the companion coupling, and by preference the forward lower corner of the channel is chamfered to coact with the 95 chamfer of the stud 11 to guide the jaw in the head of its companion.

Formed through the top and bottom walls 5 and 6, respectively, immediately to the rear of the base of the jaw are the holes 100 13 and 14, the hole 14 being located wholly to one side of the median line of the head while the hole 13 is of greater area and extends over, or spans, the median line, as

best shown in Figure 3, and formed in the top wall in advance of the hole 13 is a notch 15.

Formed in the side wall 7 immediately to 5 the rear of the holes 13 and 14 is a slot 16, and formed in the top wall 5 and bottom wall 6 adjacent the rear, open end of the head are the relatively aligned holes 17 and 18.

10 On the inside faces of the side walls 7 and 8 transversely aligned with the holes 17 and 18 are the opposite vertical ways 20 and 19.

The holes 13 and 14 are arranged to receive the coupling pin 21, whose body or 15 stem is preferably of rectangular or non-circular section and said stem carries at its inside lateral face a lifting stud 22 whose forward lower corner is chamfered for elevation by the lower, forward chamfer of the 20 channel 12 of the jaw. For the same reason the pin is provided with a second elevating element, such as 23 arranged to be moved by impingement with the upper forward corner of the jaw.

25 At the top the pin is provided with a head 25, which determines its lower limit of movement.

The pin is further provided with a manipulative element 21^a arranged for extension 30 through the slot 16.

Formed on the bottom face of the lower wall 6 of the head there are the parallel guides 28—28, and a stop 29 having a set-screw 30 for adapting the head for train 35 line couplings, not shown.

The draw bar 34 comprises a head 35 whose section permits it to be extended freely into the rear open end of the head A and through which there is formed a hole 40 36 for the reception of the pin 37 which extends through the holes 17 and 18 in the head A.

As shown the head 35 is provided with an 45 integral perforated strap 38 spaced from the lower side of the head 35 through which the pin extends and positioned between the head and strap is a key-plate 39 perforated to receive the pin 37 and provided with wings 40 which loosely reside in the ways 19 and 20.

50 The key plate 39 constructed and arranged as shown assists the pin 37 in transmitting the draw bar pull to the coupling head so that with the form of key plate shown the draw bar pull is distributed to four points 55 on the coupling head, the pin 37 transmitting the pull to the top and bottom walls 5 and 6, respectively, and the key plate 39 transmitting the pull to the side walls 7 and 8 through the wings 40 of the key plate.

60 The key plate 39 mounted in the draw bar head 35 and having the wings 40 working in the ways 19 and 20 while assisting the pin 37 in transmitting the pull to the coupling head permits relative movement, vertical 65 and rotative, between the draw bar head and

the coupling head. The amount of vertical movement permitted in the construction shown may be seen from an inspection of Fig. 3 of the drawings and comprises the distance between the bottom wall of the coupling head and the bottom surface of the draw bar head, the contact of the bottom wall of the coupling head with the draw bar head preventing further relative vertical movement between these two parts. 70

Extending rearwardly from the head 35 of the draw bar is a bifurcated stem 41 provided with a contracted mouth 42 at its rear end which is arranged to receive the end 43 of the draw bar proper 44. It is obvious 80 that the draw bar head 35 may be integral with the draw bar 44, although they are shown in two parts which may be held together, in any well-known way, as by the bolts 43^a. 85

The end 43 is provided with shoulders 45 which fit over the reduced mouth of the stem 41 and serve to connect the draw bar elements in a manner to prevent relative longitudinal movement, the stem 41 and the 90 end 43 being held together by the bolt 43^a.

As shown the forward ends of the fixed jaws 1 are inclined rearwardly and inwardly so that in the event the heads are swung on the pins 37 to not align with the trends of 95 the cars such jaws will coact to swing the coupler heads to relative alignment.

In Figure 3 we show the upper forward corner of the head 35 of the draw bar as provided with a cam-chamfer 35^a and the 100 coupling head with a bevelled rib 35^b extended transversely thereof and depending from its upper wall 5.

By this expedient the coupling head by reason of the beveled rib and the chamfer 105 of the draw bar is gravity actuated to tend toward alignment with the draw bar and thus facilitate the coupling of two cars.

In the act of coupling two cars equipped with couplings constructed as just recited, 110 the chamfers on the jaw 1 engage the elements 22 and 23 and thus lift the coupling pin 21 to permit the jaws to enter the heads to a point where the recesses 2 of the jaws will reside within the coupler heads 115 and to the rear of the coupling pins so that the heads 25 of the pins will be dropped into the jaw recesses 13 and thereby form a double or two pin coupling.

The pins and jaws serve to hold the 120 coupled heads against movement in any direction, but by reason of the pivotal connection, namely, the pins 37, the heads have flexure relative to the draw bars.

An uncoupling is effected by an elevation 125 of the coupling pins, which is accomplished by lifting both handles 21^a, which raises both coupling pins at the same time thereby releasing both jaws.

An economical advantage arising from 130

the construction of the couplings as described is that due to the making of the structure in a number of parts such as the head proper, the pins, and the two part draw bar the assemblage is facilitated and the replacement of broken or damaged pieces much reduced in cost over such couplings as are cast or formed in one piece.

What we claim:

10 1. The combination with a coupling head and a draw bar of a pin for pivotally connecting the head and draw bar, a strap carried by the draw bar and a key, said pin passing through said head, strap and key for connecting the strap and key to the head.

15 2. The combination with a coupling head and a draw bar, means for pivotally connecting the head and draw bar, a strap integrally carried by the draw bar, and a key, said first-mentioned means being pivotally connected to the key to permit relative vertical movement therebetween.

20 3. In combination with a coupler head having opposed ways in its inside face, a draw-bar arranged for extension into the head, a pin for pivotally connecting the head and bar and a key secured in said ways and engageable by said pin.

25 4. A coupler comprising a coupling head, a draw bar, a pivot pin connecting said coupling head and draw bar, and means pivotally connected to said pivot pin and coacting therewith for transmitting the

30 draw bar pull to the coupling head.

35 5. A coupler comprising a coupling head, a draw bar, a pivot pin connecting said coupling head and draw bar, and means

pivotally connected to said pivot pin and coacting therewith for transmitting the draw bar pull to the coupling head, said means and coupling head being movable relative to each other in a vertical plane.

40 6. A coupler comprising a coupling head, a draw bar, a pivot pin connecting said coupling head and draw bar, and means associated with said pivot pin for transmitting the draw bar pull to the coupling head, said means and said coupling head being relatively movable in a vertical plane and said means being revolvable relative to the pivot pin.

45 7. A coupler comprising a coupling head, a draw bar having a head, a pivot pin connecting said coupling head and said draw bar head, and means pivotally mounted in said draw bar head for assisting said pivot pin in transmitting the draw bar pull to the coupling head, said means and said coupling head being relatively movable in a vertical plane.

50 8. A coupler comprising a coupling head, having opposed vertically disposed ways, a draw bar having a head, a pivot pin connecting said coupling head and said draw bar head, and a key plate mounted in said draw bar head and having opposed wings extending into the ways in the coupling head and slideable therein, said key plate and coupling head being relatively movable in a vertical plane.

55 In testimony whereof we hereunto affix our signatures.

ONESIME H. LE COMPTE.
